UNITED STATES PATENT OFFICE.

ROLAND E. HILL, OF DECATUR, ILLINOIS, ASSIGNEE TO WILLIAMS SEALING CORPORATION, OF DECATUR, ILLINOIS, A CORPORATION OF ILLINOIS.

LEVER-TRIPPING DEVICE FOR BOTTLE-CAPPING MACHINES.

Application filed November 8, 1924. Serial No. 748,692.

This invention relates particularly to the lever tripping mechanism of a bottle capping machine, said machine being designed to apply and secure to bottles, jugs or cans, caps of the kind disclosed in Williams Patent No. 1,108,959. These caps comprise a slotted metallic skirt carrying a divided ring to which a fastening lever is secured, and are applied to the mouth of the bottle with the contracting lever in its raised position. While pressure is maintained upon the cap, the lever is thrown down for the purpose of securely fastening the cap to the bottle, inasmuch as the ring, connected to the skirt, is contracted by this downward movement of the lever and when the downward movement of the lever is completed it is locked upon the cap.

In order to trip the cap lever it is of course best to apply the pressure either at the end thereof, or to a point adjacent the end, and inasmuch as this lever swings through the arc of a circle it is desirable, and in fact may be said necessary, to have the tripping mechanism move also in the arc of a circle in order to accommodate the movement of the lever, thereby maintaining the proper contact between the tripping device and the lever at the proper point.

Furthermore, it is desirable that the tripping device should cease its tripping movement at the proper time as otherwise the neck of the bottle may be fractured by the continued pressure of the tripping device upon the lever after the operation has been completed. This becomes of importance in using the tripping device in connection with different sizes of caps as it will be understood that for large size caps a definite amount of movement will be necessary and for small caps the less movement is necessary.

In a capping device of this kind it is also of the utmost importance that the tripping action of the lever should be done as quickly as possible inasmuch as the capping machine is operated rapidly in order to accommodate quantity productions.

The object of my invention therefore is to provide a simple and efficient lever tripping device for a capping machine which will successfully perform in the manner indicated, the various functions hereinbefore referred to.

My invention therefore consists in providing a vertically movable plunger which is preferably moved in one direction by a spring

and in a reverse direction by a cam, said plunger carrying at its lower end the tripping finger which contacts with the lever of the bottle cap, and the plunger, the finger, and the guiding and cooperating parts are so constructed and arranged that at the same time the finger is moved vertically it will also be shifted laterally so that its free end will describe a curve substantially the same as the curve described by the end of the cap lever so that the tripping finger is in proper positive contact with the cap lever at all times during the tripping operation.

The invention consists also in providing in connection with said plunger, not only the proper guides, but also a stop mechanism for limiting the downward movement of said plunger so that the movement of the finger can be arrested at the proper time and undue pressure prevented.

The invention also consists in certain details of construction hereinafter set forth and described in the claims.

In the drawings forming a part of this specification, Fig. 1 is a side elevation of a tripping mechanism embodying one form of my invention; Fig. 2 is a rear or inner face view of the same; Fig. 3 is a central vertical longitudinal sectional view; Fig. 4 is a vertical sectional view of a device taken on the plane at right angles to the section of Fig. 3; Fig. 5 is a horizontal section on the line 5—5 of Fig. 2; Fig. 6 is a horizontal section on the line 6—6 of Fig. 2 and Fig. 7 is a horizontal section on the line 7—7 of Fig. 2, these sections shown in Figs. 5, 6 and 7 being slightly enlarged; Fig. 8 is a detailed view showing the tripping finger in its raised position; Fig. 9 is a detailed view showing the position of the finger about halfway lowered, the lower position of the finger being indicated in Fig. 1. Fig. 10 is a side view of one of the guide plates.

This tripping device constitutes a part of a complete rotary capping machine which is supplied with twelve or more bottles, cans or jugs, each bottle or can having a cap of the kind described automatically applied to the mouth or nozzle thereof, and after the cap has been applied to the mouth of the bottle and pressure applied thereto to firmly force the cap into contact with the mouth of the bottle, it is moved away from the cap applying mechanism and the lever of the cap tripped to complete the capping operation.

and it is this tripping mechanism which I will now describe in detail.

One part of the capping machine is a horizontal circular cam 10 having a gradual rise 5 10^a and a steep drop or descent 10^b there being a substantially flat spot 10^c at the end of the rise 10^a and which terminates in the drop 10^b .

This cam rotates with the machine in the 10 direction indicated by the arrow in Fig. 2.

A stationary arm extends radially outwardly from the center of the machine and carries at its outer end a depending arm 12 to which is connected the lever tripping device 15 which constitutes the subject matter of this application, and in the construction of which I employ a plate 13 which is secured to the depending arm 12. Rigidly connected to this plate 13 along its central longitudinal 20 line is a block 14, and rigidly connected to this centrally disposed block 14 upon each side thereof are the parallel guide plates 15 which extend from the top of the block 14 to the lower end of the plate 13. Sliding upon the 25 guide plates 15 is a plunger composed of the block 16 and plates 17 connected to the sides of the block and extending downwardly and contacting with the outer sides of the plates 15, the side portions of the plunger terminating at a point above the end of the guide plates 15 and back plate 13.

The side plates 17 are connected to the block 16 by means of the screws 16^a and the lower ends of the side plates 17 are connected 30 through the medium of a pin 18 working in straight vertical slots 19 cut in the guide plates 15, and this pin 18 also serves as a pivotal connection for the tripping finger 20 sliding vertically between the lower ends of 35 the guide plates 15 the extreme lower end 20 a of the lever being spread as shown in order to provide ample width for engagement with the capping lever inasmuch as said lever may not always rest in the same relative position. The finger 20 is also curved inwardly 40 as shown at 20^b and carries a pin 21 extending therethrough, the ends of said pin working in the cam slots 22 produced in the plates 15 adjacent their lower ends and it will be 45 noted that the upper portions of the slots are straight while the remainder of the slots are curved as hereinafter described.

It will therefore be understood that the 50 plunger slides up and down upon the guide plates and carries the tripping finger at its lower end between said guide plates, the finger being pivotally connected at its upper end to the plunger and provided intermediate 55 its ends with the laterally projecting pin portions which engage the curved slots in the guiding plates so as to impart an in-and-out lateral movement of the tripping finger at the same time that it is moved up and down.

The upper end of the block 16 has a recess 60 16 b produced therein to receive the lower end

of a coil spring 23 which passes vertically upwardly through a barrel 24 and fits into a housing 25 arranged at the upper end of the plate 13. A tension screw 26 works through the top of the housing and carries a head 26 a at its lower end within the housing for engagement with the coil spring 23. This tension screw 26 has a turning head 26 b and is also provided with a lock nut 26 c . By the adjustment of the screw 26 the proper amount 70 of tension can be provided for throwing the plunger downward. For the purpose of raising the plunger and placing the spring 23 under compression I arrange a roller 27 on the inner side of block 16 which travels upon the cam 10 riding up the incline 10^a and dropping down the steep incline 10^b as soon as the edge of the horizontal portion 10^c has been passed.

It will be understood that as the roller 80 27 travels up the incline 10^a the plunger and finger are drawn upwardly to the positions shown in Fig. 8, and when the point 10^b has been passed the spring 23 throws the plunger and finger downwardly to the position shown in Fig. 1 and Fig. 3; and about half way between the upper and lower strokes the finger will be in the position indicated in Fig. 9.

Thus it will be seen that the plunger is 90 lifted by the cam and is thrown downwardly by the spring carrying with it the tripping finger 20 and moving the same into the position indicated in Figs. 1 and 3 but owing to the 100 tripping finger 20 being provided with pin 21 working in the slots 22 in the guide plates the lower end of the tripping finger is caused to move in the arc of a circle during this movement and as the lower ends of this 105 finger 20 rest directly above the end of the capping lever 30 it will remain in contact with the outer end of this capping lever during its movement through the arc of a circle, this movement of the capping lever 30 being 110 produced by the tripping finger 20 bearing down thereon. The complete capping operation will be practically instantaneous and as the cam continues to move, the roller will begin to travel up the next incline returning 115 the tripping finger to its raised or upper position ready to act upon the next capping lever as the next bottle with the cap thereon is brought opposite the laterally enlarged end of the tripping finger.

It will of course be understood that the operations of the machine are so timed that the bottles with caps thereon will be brought 120 successively into proper juxtaposition with the tripping finger just at the proper moment for the tripping finger to operate upon the lever of the cap.

In order to limit the downward movement 125 of the plunger and tripping finger, and thereby prevent undue breakage I provide a stop 130

- screw 31 having a head 31^a which contacts with a cushion 32 arranged upon the upper end of the block 14, this screw 31 screwing into a vertical bore produced in the block 16. The screw can be turned up or down in order to regulate the length of stroke of the plunger, and a lock nut 33 is also carried by this screw for the purpose of locking the same at any desired place of adjustment. 10 This not only limits the downward movement of the plunger but it also provides a cushion to relieve the jar of the sudden movement of the plunger.

It will thus be seen that I provide a very simple and highly efficient mechanism for manipulating the fastening lever of the cap, embodying a tripping finger which not only presses upon the cap lever but also moves through exactly the same arc of a circle as 20 said lever, so as to maintain contact with the lever at all times thereby insuring positive fastening of the capping lever which completes the capping operation.

It will also be noted that the plunger 25 during the lever tripping operation is spring actuated and practically instantaneous while the return movements are more gradual, inasmuch as one capped bottle is moved away from the lever tripping mechanism and another bottle with the unfastened cap thereon is moving toward said mechanism and these various operations are so timed that the plunger with the tripping finger is completely raised and ready to descend just at 30 the moment the bottle with cap thereon and lever raised moves into proper conjunction with the lower end of the tripping finger.

The guide plates 15 have notches 15^a cut

therein to receive the plates 36 secured by bolts 37 to the block 14 and these plates 36 40 extend laterally a sufficient distance to overlap the plate members 17 of the plunger thereby guiding said plunger and holding the same to its true vertical position.

Having thus described my invention, what 45 I claim is:

1. The combination with a guide having a slot, of a vertically movable plunger, a finger pivotally connected to the end of the plunger, a pin carried by the finger and 50 working in the slot, said slot being curved to impart a lateral movement to the free end of the finger during its vertical movement.

2. In a device of the kind described, the combination with a guide, of a plunger reciprocating on said guide, a finger carried at the end of said plunger, one of said parts having a curved slot and another a pin engaging said slot and imparting to said finger a lateral movement during its vertical movement together with means for moving said finger and plunger vertically. 55

3. In a device of the kind described, the combination with a suitably supported block, of fixed guide plates having vertical and 60 curved slots, a plunger sliding upon said guide plates, a finger movable between the lower ends of the guide plates and pivotally connected to the plunger, the pivot working in the vertical slots in the guide plates, a 70 pin carried by the finger and working in the curved slots in the guide plates, and means for moving said plunger vertically.

In testimony whereof, I hereunto affix my signature.

ROLAND E. HILL.
